UNITED STATES PATENT OFFICE.

SIDNEY A. REEVE, OF TOMPKINSVILLE, NEW YORK, ASSIGNOR TO EGBERT H. GOLD,
OF CHICAGO, ILLINOIS.

STEAM-HEATING SYSTEM.

1,165,446.

Specification of Letters Patent. Patented Dec. 28, 1915.

Application filed January 5, 1914. Serial No. 810,378.

To all whom it may concern:

Be it known that I, SIDNEY A. REEVE, a citizen of the United States, residing at Tompkinsville, in the county of Richmond & State of New York, have invented certain new and useful Improvements in Steam-Heating Systems, of which the following is a specification.

My invention relates to steam heating, 10 and particularly to the heating of railway cars by steam; the primary object of the invention being the provision of an improved system of heating railway cars by steam which, having in view the peculiar conditions governing the heating of railway cars by steam, will provide a regulation of the 15 heat delivered to the car that is more accurate, reliable and that has a wider range than is provided by the car heating systems 20 now in use.

More specifically, the invention has for an object to govern the amount of heat delivered from the heating coil or other radiator, not merely, as is ordinarily done, by 25 a regulation of the pressure maintained in the coil, allowing the rate of condensation to depend entirely upon the temperature of the atmosphere in the car, but to positively vary and control the rate of condensation 30 of the steam, and consequently the amount of heat produced by the radiator, in accordance with and in proportion to the varying requirements of the car for heat. The amount of heat delivered from the radiating coil, or other radiating element, cannot be varied to any considerable extent by increasing or decreasing the pressure of steam 35 in such radiator. Moreover, there are many serious objections, as is well known, to the employment of high pressure systems in car 40 heating. In an atmospheric pressure system the amount of heat delivered depends entirely upon the rate of condensation and since the rate of condensation is only 45 slightly varied by variations in the atmosphere surrounding the radiator of a system of this sort, it does not have in itself the capacity for regulation over a sufficiently wide range to enable it to meet all conditions. It does not respond quickly enough 50 when first started up in a cold car, for example, or when there is a sudden change in the temperature of the car.

My invention improves upon the car 55 heating systems now in common use by obtaining an increased variation in the rate of

condensation of the steam in the radiator through the production of an artificial draft across the radiating surfaces of the radiator by means regulated and governed in accordance with the requirements of the car for heat. The system provides a regulation over a wide range which is exactly proportioned to the varying requirements of the car for heat and is independent of the variations of pressure in the supply pipe which, under practical conditions, are often widely variant.

A further object of the invention is to decrease the cost of installation of the heating system of a car and the amount of space which it occupies (which latter is a very important consideration) without diminution of its heating capacity. This object is attained in my system by a decrease in the size 75 of the radiator made possible by the employment of the artificial draft across the radiating surfaces.

The invention has for further objects such other new and improved constructions, 80 arrangements and devices in car heating systems as are shown in the accompanying drawings and described and claimed herein.

The invention is illustrated, in certain preferred embodiments, in the accompanying drawings, wherein—

Figure 1 is a side elevation of a car heating apparatus constructed in accordance with the invention, the flooring of the car and certain parts of the apparatus being 90 shown in section; Fig. 2 is a plan view of this apparatus; Fig. 3 is a fragmentary sectional view of the controlling devices showing the valves in a different position from their position in Fig. 1; Fig. 4, a detail elevation of the inside thermostat and its casting; Fig. 5, a view similar to Fig. 3 showing a modified construction of the controlling mechanism; Fig. 6, a view similar to Fig. 1 illustrating another modified embodiment of the invention; Fig. 7, a sectional plan view of the four-way butterfly valve forming a part of the system shown in Fig. 6; Fig. 8, a vertical section taken on line 8—8 of Fig. 7, and Fig. 9, a plan view 100 of the thermostat used to operate the four-way valve and its connections with said valve.

Like characters of reference designate 110 like parts in the several figures of the drawings.

Referring first to Figs. 1 to 4 inclusive, A

designates the train pipe ordinarily arranged under the flooring B of the car and receiving steam from the locomotive boiler, and C a radiating coil arranged in a suitable place within the car and preferably surrounded by a trunk or casing D formed with openings 10. Air is forced into the trunk D by means of a fan or blower E of any preferred type, the fan being driven by a turbine, or other suitable form of steam motor, designated F, which is arranged so as to receive steam from the train pipe A, through certain controlling mechanisms, and to exhaust into the radiator C.

15 The pressure of the steam in the train pipe, it will be understood, varies with the fluctuations of pressures in the locomotive boiler and for different cars varies with the distance of the particular car from the locomotive and with the consumption of steam by the heating systems of the cars between such particular car and the locomotive. The rapidity of condensation of steam in the radiator, and hence the requirement for 20 steam sufficient to keep the radiator full, will vary, to a certain extent, in accordance with the temperature of the atmosphere of the car, but in my system more widely according to the strength of the air blast over 25 the radiating surfaces developed by the turbine. The ratio of condensation to supply will not be constant for different pressures in the supply pipe, even when the factor of the temperature of the atmosphere in the 30 car is ignored, since it will require a certain velocity of steam through the turbine to move the fan at all, and the speed of the fan, when in motion, and hence the strength of the air blast produced thereby, will be 35 greater in proportion to the amount of steam introduced into the radiator at the higher supply pipe pressures than at the lower. It is necessary, therefore, in order, on the one hand, that the radiator should be capable of 40 operating under all conditions to deliver a maximum amount of heat to the car when necessary, and, on the other hand, that there should not be, under any conditions, a waste of steam or an overheating of the car when 45 a minimum of heat is desired, that a controlling mechanism should be provided which will be self-adjusting to the variant conditions produced by changes in supply pipe pressure and changes in the requirements of 50 the car for heat. Furthermore, in order that the amount of heat delivered should correspond accurately to the actual requirements of the car for heat the controlling mechanism should be made to respond directly to 55 changes of temperature in the car.

60 One form of controlling mechanism calculated to function so as to produce this desired result is shown in Figs. 1 to 4 inclusive, and is made up of the following parts: G and H are two valves interposed in the

steam conduit between the supply pipe and the turbine and radiator; the valve G, the one nearest the supply pipe, being controlled by a thermostat J located at the outlet of the radiator, and preferably outside of the car, the other valve H being controlled by a thermostat K located within the car. The thermostat J is constructed so as to operate at a temperature a little below that of steam, preferably at about 170° Fahrenheit, while the critical temperature of the thermostat K is the desired temperature of the car, this thermostat being preferably adjustable to vary its critical temperature as devices of this sort usually are. The valves G and H are arranged in a valve casing 11, the valve G controlling a port 12 between chambers 13 and 14 and the valve H, controlling a port 15 between the chamber 14 and a chamber 16 and also a port 17 between the chamber 16 and a chamber 18, port 15 being preferably wider than the face of its valve. A pipe 19 leads from the train pipe A to the chamber 13. A pipe 20 leads from chamber 16 to the turbine nozzles 21. The steam from the turbine passes into the radiator through a pipe 22. The return end of the radiator discharges through a port 23 into a conduit 24 which leads to the casing 25 of the outside thermostat J and communicates with the chamber 18 through the hollow piston valve 26 which is secured to the stem 27 of valve H and serves to substantially close port 23 when the valve H is raised although preferably the valve 26 is formed with a drip port 28 which, by registering with port 23, provides an outlet for water of condensation from the radiator but of such small area that no appreciable amount of steam will back up into the radiator through it. On the under side of the valve H, which is a solid piston valve, is preferably arranged or formed a smaller conical valve 29 adapted to bear upon a conical seat 30 formed around the port 17. Below the valve 29, on the same stem, is a piston valve 31 of the same diameter as the minimum of port 17, and preferably formed with triangular ports 32 arranged so that the effective size of the opening between chambers 16 and 18 is gradually increased as the valve structure H—29—31 is raised. The valve H and the other valves arranged on the same stem, are operated by the thermostat K through any suitable mechanism. I have shown the valve stem 27 pivoted to the longer arm of a multiplying bell crank 33 which latter is pivoted to a standard 34 on the valve casing 11 and has pivoted to its shorter arm a rod 35 against which the thermostat K bears, the latter, which is shown as a hollow metallic diaphragm type of thermostat, is arranged within a casing 36 and is adjustable by means of an abutment screw 37 carrying an indicator hand 38 arranged over a dial 39 on the 130

casing 36. The thermostat J is shown as the same type of thermostat, the valve G being carried on the end of a rod 40 supported on the diaphragm member.

5 The operation of the apparatus just described is as follows: With the valve G standing away from its seat and the valve H below the port 15 steam will enter the turbine F at a pressure determined by the existing pressure in the train pipe. With any substantial pressure in the train pipe the turbine will be set in motion and operate the blower E so that air is forced through the air trunk D in contact with the radiator C 10 and after being heated will be discharged into the car through the openings 10. The valves G and H will remain in this position so long as the radiator is not completely filled with steam at atmospheric pressure 15 and so long as the temperature of the car is below the temperature desired. When the temperature of the car reaches the temperature at which thermostat K is set to act, this thermostat will expand and by raising 20 valve H so as to shut off communication between chambers 14 and 16, will stop the supply of steam to the turbine and at the same time to the radiator. The steam passing through port 15 will be by-passed to thermostat 25 J expanding the same so as to close the port 12 and prevent the waste of steam by shutting off the supply. At the same time the valve 26 substantially closes communication between chamber 18 and the return 30 end of the radiator leaving, however, a small drip port open to allow the escape of water of condensation.

Under conditions of maximum demand for heat, when both valves are wide open, if 40 the train pipe pressure be high it is likely that the radiator will not be completely filled with steam. This, if true, would be due to the greater efficiency of turbine and fan under higher steam pressure and consequent speed. That this will be so cannot be 45 stated positively, because the comparative rate of increase in fan efficiency and in radiator activity cannot be known. But such a possible deficit of steam in the radiator 50 should be mentioned as being compatible with the very highest rate of heat supply to the car. It would exist, if at all, only by reason of the multiplied rate of heat abstraction from the coil due to the strong air 55 blast, which rate is faster than the maximum inflow of steam through wide open valves under high pressure. The first effect of any action of the thermostat K to reduce the heat supply from this maximum would 60 be to raise slightly the small valve 31 and simultaneously to partially close the pathway to chamber 16, so that the pressure at the turbine nozzle is reduced and the speed of turbine and fan reduced. The reduced 65 air blast decreases the rate at which heat is supplied to the car. In this way the rate of heat supply is variable throughout the entire range in speed of the turbine, which is a very wide range, and this constitutes an important method of regulation by my apparatus. It is quite possible, if not probable, that this action will lead to the complete filling of the radiator with steam, where before it was only partly filled; but this does not imply a greater, but a less, 70 supply of heat to the car, the filling being due to the decreased rate of abstraction by the air blast. Should this be so, the thermostat J will enter, controlling the steam supply in conjunction with thermostat K, to 75 the end that no steam be wasted. Beyond this method of regulation, the controlling valves may further shut off the supply of steam, or by-pass so much of it direct to the thermostat J, that the turbine stops altogether. This leaves the radiator full of steam, but with no air blast traversing it. This cannot happen, it is understood, unless the by-pass is open. As soon as thermostat 80 K closes the by-pass the steam required to 85 keep thermostat J warm must be sufficient to start the turbine. Beyond this step in regulation, again, the construction of valve element H—29—31 permits a still further range of regulation of heat to the car, by admitting to the radiator only enough steam to fill it partially, but this time with no air blast traversing it. The discharge end of the radiator need not now be filled with steam, because the by-pass valve sends steam 90 enough to thermostat J to keep the main supply open. At the same time, the original need for keeping the discharge end full of steam, to prevent freezing, no longer applies, because the thermostat K will take 95 this position only when the car is almost warm enough, with no possibility of freezing within the car; while the thermostat J, if outside the car, is kept warm by the by-passed steam. It is to make possible this 100 method of operation that the valve 31 is made small and with the triangular ports 32, to permit the thermostat K to send small quantities of steam to the thermostat J, and that the valve H is made narrower than its 105 port, so that it may take a number of regulative positions between either closing all steam from the radiator or shutting it all from the by-pass.

The extreme action of thermostat K, so 110 as to close all passageways for steam to the radiator, constitutes the final step in the regulation of rate of heat supply to the car. It is therefore plain that my apparatus combines three distinct methods of regulation, 115 all of which are needed to make the most effective heat regulation. These methods depend upon (1) the time during which the heat is either on or off, a method which is not, of itself, new; (2) the method de- 120

pending upon the speed of the fan, a method which could not of itself be used practicably but which is of great importance in connection with the other provisions made by the 5 apparatus; and (3) the method depending upon partial filling of the radiator while it rests in quiescent air, a method depending upon the arrangement of valve H—29—31 for throwing more or less steam into the 10 radiator (all quantities being less than that required for starting the fan) while keeping thermostat J warm by the by-pass. In the first case, where the fan is revolving at maximum speed under high train pressure, 15 so as to condense the steam before it can completely traverse the radiator, there is apparent danger of freezing the outlet; but the danger is more apparent than real, for the outlet is a large passageway, not restricted by any valve, and the time during 20 which the state of affairs described could continue would be limited. The car would warm up very rapidly, under these assumptions, and it is inconceivable that ice could 25 form fast enough at the outlet to close it before the thermostat K had brought the by-pass into play and let enough steam leak directly to thermostat J to keep it above the freezing point.

30 Fig. 5 shows an arrangement of the controlling devices which is similar in principle to that shown in Figs. 1 to 4 inclusive. In this case, however, the main valve controlled by the inside thermostat K, this valve 35 being here designated H', is as wide as or wider than the port 15'. This arrangement contemplates only two positions of the valve, namely, one above the port 15' and the other below it though the former may 40 be graduated. The construction is further modified by the omission of the valve which closes the return end of the radiator, the radiator in Fig. 5 communicating through pipe 41 with a thermostat casing 42 at a 45 point close to the thermostat J so that there will be no danger that steam by-passed to the thermostat will back up or be thrown into the return end of the radiator.

In Figs. 6 to 9 inclusive, a four-way butterfly valve is employed for directing the steam passing valve G² either to the turbine and radiator or to the outside thermostat J². The four-way valve as a whole is 50 designated L. The valve G², and thermostat J², in this arrangement, constitute parts of a vapor regulator of a familiar type which are interposed between the train pipe A and the four-way valve L. The vapor regulator comprises a casing 43 divided into 55 two chambers 44 and 45 communicating by a port 46 controlled by the valve G², steam entering the chamber 44 through a pipe 47 leading from the train pipe A. A pipe 48 leads to the four-way valve L. Valve G² 60 is operated from thermostat J² through the

interposition of rods 49, 50 and bell crank 51. The four-way valve device consists of a casing divided into four chambers 52, 53, 54 and 55, pipe 48 leading to chamber 52, and of the rotary valve member 56 having 70 the stem 57 and handle 58 which latter is connected to a bell crank 59 operated through the rod 60 by the thermostat K² arranged in the car. A pipe 61 leads from chamber 53 to the turbine F. A pipe 62 75 leads from the return end of the radiator to the chamber 54. A pipe 63 leads from chamber 55 to the casing 64 of thermostat J². The valve 56 is arranged so as in one position to put chamber 52 in communication with chamber 53 and chamber 54 in communication with chamber 55 directing the steam passing valve G² to the turbine and radiator and providing an outlet from the radiator to the thermostat casing 64, and 80 in its other position to put chamber 52 in communication with chamber 55 so that the steam passing the valve G² will be bypassed to thermostat J². In this position of the valve 56 a port 65 in its lower disk 85 66 will register with a port 67 opening out of chambers 53, 54 so that a drip passageway is provided to allow the discharge of water of condensation.

While I have described my invention in 95 certain preferred embodiments, it will be understood that further modifications could be made without departure from the invention. Therefore I do not wish to be understood as limiting the invention to the particular arrangements, constructions and devices shown and described.

I claim:

1. In a car heating system, the combination 105 with a supply pipe and a radiator adapted to receive steam from said supply pipe, of a thermostatic device for controlling the passage of the medium through the radiator comprising a thermostat at the outlet of the radiator, means for producing a 110 draft over the radiating surfaces of said radiator comprising a motor, and a thermostat in the car for automatically controlling said motor.

2. In a car heating system, the combination 115 with a supply pipe and a radiator adapted to receive steam from said supply pipe, of a valve interposed between said supply pipe and radiator, a thermostat at the outlet end of the radiator for controlling 120 said valve, means for producing a draft over the radiating surfaces of said radiator comprising a motor, and a thermostat in the car for controlling said motor.

3. In a car heating system, the combination 125 with a supply pipe and a radiator adapted to receive steam from said supply pipe, of a thermostatic device for controlling the passage of the medium through the radiator comprising a thermostat arranged at 130

- the outlet of said radiator, means for producing a draft over the radiating surfaces of said radiator comprising a motor, a valve to govern the introduction of steam into said radiator, and thermostatic means in the car for controlling said motor and valve. 5
4. In a car heating system, the combination with a supply pipe and a radiator adapted to receive steam from said supply pipe, of means for producing a draft over the radiating surfaces of said radiator comprising a motor, a valve to govern the introduction of steam into the radiator, thermostatic means in the car for controlling said motor and valve, a valve interposed between the first mentioned valve and the supply pipe adapted to vary the amount of steam introduced into the system, and a thermostat controlled by the temperature at the discharge end of said system for operating said last named valve. 10
5. In a car heating system, the combination with a supply pipe and a radiator adapted to receive steam from said supply pipe, of means for producing a draft over the radiating surfaces of said radiator comprising a motor operated by steam from said supply pipe and through which steam from the supply pipe passes to the radiator, a valve to govern the flow of steam to said motor, a thermostat within the car for controlling said valve, a valve interposed between said first mentioned valve and the supply pipe adapted to vary the amount of steam introduced into the system, and a thermostat controlled by the temperature at the discharge end of said system for operating said last named valve. 15
6. In a car heating system, the combination with a supply pipe and a radiator adapted to receive steam from said supply pipe, of means for producing a draft over the radiating surfaces of said radiator comprising a motor, a valve interposed between the supply pipe and said radiator, a thermostat at the outlet of said radiator for controlling said valve, a second valve interposed between the first named valve and the radiator adapted, in one position, to allow the flow of steam into the radiator and in another position to by-pass the steam to the thermostat at the outlet of the radiator, and thermostatic means in the car for controlling said last named valve and the motor. 20
7. In a car heating system, the combination with a supply pipe and a radiator adapted to receive steam from said supply pipe, of means for producing a draft over the radiating surfaces of said radiator comprising a motor, a valve interposed between the supply pipe and said radiator, a thermostat at the outlet of said radiator for controlling said valve, a second valve interposed between the first named valve and the radiator adapted in one position to allow the flow of steam into the radiator, in another position to by-pass the steam to the thermostat at the outlet of the radiator and in an intermediate position to allow some of the steam to go to the radiator and some to said thermostat, and thermostatic means in the car for controlling said last named valve and the motor. 25
8. In a car heating system, the combination with a supply pipe and a radiator adapted to receive steam from said supply pipe, of a thermostatic device for controlling the passage of the medium through the radiator comprising a thermostat at the outlet of the radiator, means for producing a draft over the radiating surfaces of said radiator comprising a motor operated by steam from said supply pipe and through which steam passes from the supply to the radiator, and a thermostat in the car for automatically controlling said motor. 30
9. In a car heating system, the combination with a supply pipe and a radiator adapted to receive steam from said supply pipe, of means for producing a draft over the radiating surfaces of said radiator comprising a motor operated by steam from said supply pipe and through which steam from the supply pipe passes to the radiator, a valve to govern the flow of steam to said motor, a thermostat within the car for controlling said valve, a valve interposed between said first mentioned valve and the supply pipe adapted to vary the amount of steam introduced into the system, and a thermostat controlled by the temperature at the discharge end of said system for operating said last named valve. 35
10. In a car heating system, the combination with a supply pipe and a radiator adapted to receive steam from said supply pipe, of means for producing a draft over the radiating surfaces of said radiator comprising a motor operated by steam from said supply pipe and through which steam from the supply pipe passes to the radiator, a valve to govern the flow of steam to said motor, a thermostat in the car for controlling said valve, said radiator discharging without the car, a valve interposed between said first named valve and the supply pipe, and a thermostat positioned without the car and in the radiator discharge and controlling said last named valve. 40
11. In a car heating system, the combination with a supply pipe and a radiator adapted to receive steam from said supply pipe, of means for producing a draft over the radiating surfaces of said radiator comprising a motor operated by steam from said supply pipe and through which steam from the supply pipe passes to the radiator, a valve to govern the flow of steam to said motor, a thermostat for controlling said valve, a valve interposed between the supply pipe and said first named valve, and a thermostat at the outlet of the radiator for controlling said last mentioned valve. 45
12. In a car heating system, the combination with a supply pipe and a radiator adapted to receive steam from said supply pipe, of means for producing a draft over the radiating surfaces of said radiator comprising a motor operated by steam from said supply pipe and through which steam from the supply pipe passes to the radiator, a valve to govern the flow of steam to said motor, a thermostat within the car for controlling said valve, a valve interposed between the supply pipe and said first named valve, and a thermostat at the outlet of the radiator for controlling said last mentioned valve. 50

- tion with a supply pipe and a radiator adapted to receive steam from said supply pipe, of means for producing a draft over the radiating surfaces of said radiator comprising a motor operated by steam from said supply pipe and through which steam from the supply pipe passes to the radiator, a valve to govern the flow of steam to said motor, a thermostat for controlling said 5 valve, a pressure reducing valve interposed between the first named valve and said supply pipe, and a thermostat positioned in the discharge from said radiator and controlling said pressure reducing valve.
- 10 13. In a car heating system, the combination with a supply pipe and a radiator adapted to receive steam from said supply pipe, means for providing a draft across the radiating surfaces of said radiator comprising a motor operated by steam from said supply pipe and delivering steam into said radiator, two valves arranged between the supply pipe and the motor, a thermostat in the car to control one of said valves, and a 15 thermostat at the outlet of the radiator to control the other of said valves.
14. In a car heating system, the combination with a supply pipe and a radiator adapted to receive steam from said supply 20 pipe, of means for providing a draft across the radiating surfaces of said radiator comprising a motor operated by steam from said supply pipe and delivering steam into said radiator, two valves arranged between the supply pipe and the motor, a thermostat in the car to control the valve nearest the motor, and a thermostat at the outlet to control the other valve.
- 25 15. In a car heating system, the combination with a supply pipe and a radiator adapted to receive steam from said supply pipe, of means for providing a draft across the radiating surfaces of said radiator comprising a motor operated by steam from said supply pipe and delivering steam into said radiator, two valves arranged between the supply pipe and the motor, a thermostat in the car to control the valve nearest the motor, and a thermostat at the outlet to control the other valve.
- 30 16. In a car heating system, the combination with a supply pipe and a radiator adapted to receive steam from said supply pipe, of means for providing a draft across the radiating surfaces of said radiator comprising a motor operated by steam from said supply pipe and delivering steam into said radiator, two valves arranged between the supply pipe and the motor, a thermostat in the car to control the valve nearest the motor, and a thermostat at the outlet to control the other valve.
- 35 17. In a car heating system, a radiator, a thermostat situated at its outlet and controlling its inlet, a motor arranged to drive a blast of air over the radiator and adapted to be operated actively by a major supply of steam while permitting minor supplies to traverse it without effecting motion, a valve interposed between said inlet and the motor and radiator, and a thermostat within the car to control said valve and adapted to regulate the steam supply to the motor and the radiator through various degrees of said major and minor magnitude.
- 40 18. In a car heating system, the combination with a supply pipe and a radiator adapted to receive steam from said supply pipe, of means for producing a draft over the radiating surfaces of said radiator, comprising a motor operated by steam from said supply pipe and through which steam passes from the supply to the radiator, a valve interposed between the supply pipe and said motor, and a thermostat at the outlet of said radiator for controlling said valve.
- 45 19. In a car heating system, the combination with a supply pipe and a radiator adapted to receive steam from said supply pipe, of means for producing a draft over the radiating surfaces of said radiator, comprising a motor operated by steam from said supply pipe and through which steam passes from the supply pipe to the radiator, a valve interposed between the supply pipe and said motor, a thermostat at the outlet of said radiator for controlling said valve, and a second valve interposed between said first named valve and the motor adapted, in one position, to allow the flow of steam into the motor and radiator and in another position to by-pass the steam to said thermostat.
